Primary Examiner — Andrew Kerr*Assistant Examiner* — Chariton Alexakis(74) *Attorney, Agent, or Firm* — Grogan, Tuccillo & Vanderleeden LLP(57) **CLAIM**

The ornamental design for a blade for food blender, as shown and described.

DESCRIPTION

FIG. 1 is a top perspective view of a blade for food blender showing a new design;

FIG. 2 is a bottom perspective view thereof;

FIG. 3 is a left side elevational view thereof, the right side being a mirror image;

FIG. 4 is a front elevational view thereof, the rear being a mirror image;

FIG. 5 is a top plan view thereof; and,

FIG. 6 is a bottom plan view thereof.

The broken lines in the drawings depict portions of the blade for food blender that form no part of the claimed design.

1 Claim, 6 Drawing Sheets(56)
